Fig. 4.

UNITED STATES PATENT OFFICE.

WILLIAM MCK. BRAYBROOKS, OF PHILADELPHIA, PENNSYLVANIA, ASSIGNOR TO
GULF OIL BURNER COMPANY, OF PITTSBURGH, PENNSYLVANIA, A CORPORATION
OF PENNSYLVANIA.

MOUNTING FOR OIL BURNERS.

Application filed December 5, 1927. Serial No. 237,874.

My invention relates to mountings for oil burners and more particularly has reference to ignition mountings for oil burners wherein the oil and air mixture discharged from the burner nozzle is ignited by means of an electric arc which is produced between two electrodes positioned adjacent the discharge nozzle of the burner.

It is an object of my invention to provide a mounting for the burner nozzle and electrodes of an electrically ignited oil burner wherein the electrode points are firmly fixed relative to the nozzle when the device is once assembled and wherein the mechanical and thermal arrangement is such that the possibility of any change in the relative positions of the electrode points and nozzle is reduced to a minimum.

It is a further object of my invention to provide a mounting of the character indicated wherein the parts of the assembly are suitably protected from the heat of the furnace so that they will not become impaired.

According to my invention the oil and air pipe, nozzle, electrodes, and the means for fastening the electrodes and pipe are built into one complete unit which is adapted for insertion into the fire door of the boiler or furnace to which the device is to be applied. The complete unit represents a compact structure for holding the electrodes in fixed position relative to the nozzle irrespective of thermal conditions within the furnace, the complete device being simple in construction and readily assembled.

Briefly stated my invention comprises a casing, preferably cylindrical and made of seamless steel, in which there is provided a clamp firmly held to the oil pipe and casing so that there can be no relative movement between the pipe and casing nor between the clamp and the oil pipe. To the underside of the clamp is fastened an insulating block designed to firmly hold between itself and a second insulating block insulating tubes for the reception of electrodes. The clamp and the insulating blocks are preferably shielded from the heat of the burner by a plate of suitable heat insulating material positioned within the steel casing between the supporting structure and the source of heat.

For a more detailed understanding of the invention reference will be had to the accompanying drawings wherein there is shown a

preferred embodiment of my invention but it is to be understood that the invention is by no means limited to the specific structure illustrated.

In the drawings, wherein like numerals in the different views refer to similar elements of construction, Fig. 1 represents a vertical section through the complete mounting;

Fig. 2 is a section on the line 2—2 of Fig. 1 looking to the right;

Fig. 3 is a section on the line 3—3 of Fig. 1 looking to the left;

Fig. 4 is a horizontal sectional view taken on the line 4—4 of Fig. 1;

Fig. 5 is a vertical sectional view on the line 5—5 of Fig. 1; and

Fig. 6 is an end view of the device showing the relative position of the burner nozzle and electrode points.

Referring more particularly to the drawings, the numeral 10 indicates a cylindrical casing or tube preferably constructed of seamless steel and closed by end plates 11 and 12, the end plate 11 having an opening 13 for the oil and air pipe hereinafter referred to and the end plate 12 having openings 14 and 15 for the oil and air pipe and electrodes respectively. The end plate 11 is held firmly to the casing 10 by means of flanges 16 and bolts 17 and the plate 12 by means of the counter sunk flat head screws 17' on the nozzle end of the casing. The casing 10 is provided with a circular opening 18 for the lead-in wires of the electrical connections and to permit access to the electric terminals.

Within the casing 10 there is provided a clamp, preferably of cast iron, comprising the upper element 19 and the lower element 20, the top of the element 19 being arched as shown to conform in shape with the interior of casing 10. Semi-circular openings 19^a and 20^a are cut in the adjacent faces of the elements 19 and 20 respectively for reception of the pipe 21 to which is supplied an oil-air mixture from any suitable source. Openings 22 are formed in alignment through the clamping elements 19 and 20, the openings in the latter being threaded, for reception of the screw threaded bolts 23 which pass through suitable openings in the casing 10. Openings 22 are so spaced that notches must be made in pipe 21 to permit insertion of bolts 23. A block 24 having openings in alignment with the openings through the cas-

ing and elements 19 and 20 is provided exterior of the casing to furnish a tight connection between the casing and the bolts 23. By this arrangement it will be seen that the oil 5 and air pipe 21 is clamped firmly to the casing 10 so that there can be no relative movement between the casing and the pipe.

As shown, the portion 20 of the clamp is provided with laterally extending flanges 25, 10 these flanges having openings therethrough for reception of screws 26. By means of these screws there is held firmly to the element 20 a block 27 of suitable insulating material, the block 27 being provided with flanges 28 15 and openings therethrough for the screws 26. The block 27 is provided with vertical openings as shown at 29 (Figs. 2, 4 and 5) extending partially therethrough, holes 30 being bored from the openings 29 through the block. 20 Beneath the block 27 is a second block 32, also of suitable insulating material, this block 32 having openings 29' in its under face corresponding to and in alignment with the openings 29 in the block 27. Holes 30' are bored 25 from the openings 29' through the block 32, these holes being in alignment with the holes 30 in the block 27. Screws 31 fit into the openings 29' and through the holes 30 and 30' and by means of nuts 31' in the openings 30 firmly hold the blocks 27 and 32 in fixed 30 position. Semi-circular grooves 33 are cut into the adjacent faces of the blocks 27 and 32 for receiving insulating members 34.

By the construction just described it will be 35 seen that the insulating members 34 are held firmly and rigidly between the blocks 27 and 32, these blocks being in turn secured firmly to the element 20 of the oil pipe clamping device by the screws 26 and the oil pipe and 40 clamp being held in fixed relation with respect to the casing 10 by means of the upper element 19 of the clamp, bolts 23 and block 24. There is consequently produced a rigid attachment of the members 34, oil pipe 21, and 45 casing 10 so that there can be no relative movement between these elements of the device.

The insulating members 34 are bored centrally to form tubes for reception of electrodes 50 35 which fit snugly therein. The extremities of the electrodes are bent toward each other as shown in Figs. 4 and 6 to form electrode points 36 adjacent burner nozzle 27 attached to pipe 21 by coupling 37. The opposite 55 ends of the electrodes are threaded as shown at 38 (Fig. 1) and provided with nuts 39 forming terminals for the lead-in wires. In the preferred form of the invention pins 40 are positioned in holes through the electrodes, 60 these pins fitting snugly into grooves 40' in the ends of the tubes 34 when the nuts 39 are tightened. The pins 40 are located at such a point in the electrodes that when the former are snugly into grooves 40' in the ends of the 65 tubes 34 the electrode points 36 are in their

proper positions with respect to the burner nozzle. The position of the electrodes with respect to the burner nozzle 37 may be adjusted by loosening nuts 31' and screws 31, thereby releasing the clamping action of block 70 32, and changing the position of insulating tubes 34 and electrodes 35 relative to the blocks 27 and 32 and then re-tightening the nuts and screws.

In order to protect the clamping elements 75 19 and 20 and the insulating blocks 27 and 32 from the heat of the burner there is provided within the casing 10 a plate 41 of any suitable heat insulating material. This plate is preferably held against the clamping elements and the blocks by means of screws 42 fitting into appropriate openings 43 in the block 27. The heat insulating plate 41 (Fig. 3) is circular to conform in shape and size 80 with the interior of the casing 10 and is provided with the upper opening 44 and lower openings 45 for the oil and air pipe 21 and the tubes 34 respectively.

From the foregoing it will be seen that I have devised a compact and simple mounting 90 for an oil burner pipe and electrodes wherein the electrode points are rigidly held in fixed position with respect to the burner nozzle and wherein there can be little or no change in the relative position of the casing, electrode 95 points, and nozzle. The complete unit permits of ready assemblage and may be easily taken apart when necessary, all parts within the outer casing being protected from the heat of the furnace.

While I have shown and described in detail a particular form of my invention, it will be understood that this is for the purpose of illustration only and that various changes and modifications may be made therein without departing from the scope and spirit of the invention as defined in the appended 105 claims.

Having described my invention what I claim and desire to secure by Letters Patent 110 of the United States is:

1. An ignition mounting for oil burners comprising a casing, an oil pipe mounted in said casing and terminating in a burner nozzle exterior of the casing, electrodes 115 mounted in said casing and extending beyond the same adjacent said nozzle, complementary oil pipe supporting means, and complementary electrode supporting means, one part of said oil pipe supporting means secured to one part of said electrode supporting means and the other part of the oil pipe supporting means rigidly secured to said casing.

2. An ignition mounting for oil burners 125 comprising a casing, an oil pipe mounted in said casing and terminating in a burner nozzle exterior of the casing, electrodes mounted in said casing and terminating exterior of the casing adjacent said nozzle, and 130

complementary oil pipe and electrode supporting means, one part of said oil pipe supporting means secured to one part of said electrode supporting means and the other 5 part of the oil pipe supporting means secured to said casing for holding said oil pipe and electrodes in fixed position relative to each other and to the casing to prevent relative movement of said casing, oil pipe, and electrodes.

3. An ignition mounting for oil burners comprising a casing, an oil pipe extending through said casing, complementary clamping means within said casing for holding said 15 pipe in fixed position relative to the casing, blocks within said casing, electrodes between said blocks, means for holding said electrodes firmly between said blocks, and means for rigidly attaching one of said blocks to one 20 part of said complementary clamping means.

4. An ignition mounting for oil burners comprising a casing, an oil pipe extending through said casing and terminating in a nozzle exterior of the casing, complementary 25 clamping means engaging said oil pipe and having one part fixed to said casing, electrode engaging means in said casing and fastened to said clamping means, and electrodes mounted in said engaging means, said electrodes 30 extending beyond the casing and terminating adjacent said nozzle.

5. An ignition mounting for oil burners comprising a casing, an oil pipe extending through said casing and terminating exterior 35 thereof in a nozzle, clamping means within said casing engaging said oil pipe and fixed to the casing, an insulating block fastened to said clamping means, a second insulating block attached to said first mentioned insulating 40 block, and electrodes between said blocks, said electrodes terminating exterior of the casing adjacent said nozzle.

6. An ignition mounting for oil burners comprising a casing, an oil pipe extending 45 through said casing, clamping means within said casing engaging said oil pipe and fixed to the casing, an insulating block fastened to said clamping means, a second insulating block fixed to said first mentioned insulating 50 block, tubes mounted between said blocks,

and electrodes in said tubes, said electrodes terminating exterior of the casing adjacent said nozzle.

7. An ignition mounting for oil burners comprising a casing, an oil pipe extending 55 through said casing and terminating in a nozzle exterior of the casing, clamping means in said casing engaging said oil pipe and fixed to the casing, a block fastened to said clamping means, a second block attached to 60 said first mentioned block, insulating tubes between said blocks, electrodes in said tubes and terminating exterior of the casing adjacent said nozzle, pins in said electrodes, and grooves in said tubes for receiving said pins. 65

8. An ignition mounting for oil burners comprising a casing, an oil pipe extending through said casing and terminating in a nozzle exterior of the casing, clamping means within said casing engaging the oil pipe and 70 fixed to said casing, electrode supporting means within said casing and fixed to said clamping means, electrodes mounted in said supporting means and terminating exterior 75 of the casing adjacent said nozzle, and an insulating plate within the casing for protecting said clamping means and supporting means from the heat of the burner.

9. An ignition mounting for oil burners comprising a casing, a two-part complementary burner support, a two-part complementary electrode support, means for assembling the supports adjacent each other and in operative relation to each other, means for attaching the assemblage inside the casing, an oil 80 pipe mounted in said casing and carried by the oil burner support and electrodes mounted in said casing and carried by the electrode supports. 85

10. An ignition mounting for oil burners comprising an oil pipe support having two separable parts, an electrode support comprising two separable parts, an oil pipe carried by the oil pipe support, electrodes carried 90 by the electrode support and means for assembling two supports adjacent each other and in operative relation to each other. 95

In testimony whereof, I have hereunto affixed my signature.

WILLIAM MCK. BRAYBROOKS.
